UNITED STATES PATENT OFFICE.

CHARLES EDMOND DELLENBARGER, OF CHICAGO, ILLINOIS, ASSIGNOR TO PAUL CARPENTER, OF CHICAGO, ILLINOIS.

GAME APPARATUS.

1,282,386.

Specification of Letters Patent. Patented Oct. 22, 1918.

Application filed June 29, 1914. Serial No. 847,950.

To all whom it may concern:

Be it known that I, CHARLES EDMOND DELLENBARGER, a citizen of the United States, and a resident of Chicago, in the State of Illinois, have invented certain new and useful Improvements in Game Apparatus, of which the following is a specification.

My present invention relates in general to games, and more particularly to game boards employing movable figures, and has special reference to the provision of an improved form of game board wherein certain of the figures are detachably connected thereto.

More specifically my invention relates to improvements in apparatus for playing the game of baseball, wherein I provide a base-board representing a baseball field, a series of stationary figures representing the in-fielders, the out-fielders, and the catcher, oppositely disposed pivoted figures representing the pitcher and the batsman, a plurality of detachable figures representing base runners, and means for conveying the figures representing base runners about the diamond which is represented on said base, said several figures and the mechanism for actuating and conveying the same being arranged and operable to give an approximate representation of the game of baseball as it is actually played.

The principal objects of my present invention are the provision of improved means for manipulating the figures representing base runners; the provision of improved means for conveying them about the circuit of the bases; the provision of improved means for detachably securing them to said conveying means; the provision of improved means for detachably securing the figures representing players in their respective positions; the provision of improved means for pivotally mounting certain of the figures representing players, more especially the pitcher and the batsman, for the acts, respectively, of throwing and batting the ball; the provision of improved means for securing an abrupt partial rotation of such figures in accomplishing such throwing and batting movements; the provision of improved means for manual manipulation of such operating means; the provision of improved means for catching the thrown or batted ball; together with such further and additional objects as may hereinafter appear.

In attaining the foregoing objects and certain advantages to be below disclosed, I have provided a construction, a preferred embodiment of which is illustrated in the accompanying drawings, wherein—

Figure 1 is a plan view of the game base-board with certain of the several figures used in playing the game in position therein;

Fig. 2 is a sectional view taken on the line 2—2 of Fig. 1, the figures of the pitcher and batter being omitted;

Fig. 3 is a fragmentary elevational view of part of the base-runner conveyer-mechanism showing one of the base runner figures in position therein;

Figs. 4 and 5 are respectively a side elevation and a perspective view of certain of the details of the construction shown in Fig. 3;

Fig. 6 is an elevational view of the figure representing the batsman illustrative of the means of pivotally supporting the same and the means for securing the abrupt partial rotation of the figure;

Fig. 7 is a sectional plan view with the casing removed taken on the line 7—7 of Fig. 6, illustrative of certain details of construction of the figure releasing trigger;

Fig. 8 is a sectional plan view taken on the line 8—8 of Fig. 6, illustrative of the construction of the stop whereby the rotative movement of the figure is terminated;

Fig. 9 is a sectional plan view taken on the line 9—9 of Fig. 6, illustrative of the means for varying the tension on the driving spring by means of which the rotary motion is imparted to the figure;

Fig. 10 is a fragmentary elevational view, partly in section, illustrative of a detail of construction of the figure releasing trigger;

Figs. 11 and 12 are respectively a plan and an edgewise view of a modified form of support employed in connection with the device of Fig. 3; and

Figs. 13 and 14 are respectively an edgewise and a plan view of a further modified form of such support.

Referring now more particularly to Fig. 1 of the drawings, it will be noted that I have here shown a supporting base, 20, which is preferably made in the form of a rectangle of sheet metal constituting the walls of the ball field, a bottom, 22, detachably secured thereto and a false bottom 23 on which the representation of the ball field

is painted, and by which the several figures representing the players are supported.

The outline of the diamond is made by the slot 24 preferably rectangular, the function 5 of which will hereafter appear, the usual bases being represented at 25, 26, 27, and the home plate at 28. The customary in-fielders and out-fielders are indicated at 29 and are each secured in position relatively to the 10 field by an extension 30 passing through the false bottom 23, a collar 31 and set screw 32 being utilized to detachably hold them in fixed position.

The arms 33 of each fielder 29 support a 15 ring 34 which in turn supports a bag which is preferably formed of flexible fabric and serves to aid in the catching of any balls that strike such bag or adjacent parts of the figure. The catcher 29^a is similarly formed 20 and mounted and provided with a similar bag.

Adjacent the catcher is pivotally mounted a figure 36 provided with a representation 37, of a bat, and opposite to such figure 36 25 and toward the base 26 is provided a similar figure 38 provided with a cup shaped extension 39 adapted to hold a ball, the figures 36 and 38 being similar in construction, and operated in a manner to be hereinbelow 30 described. The figures employed as base runners are indicated at 40, and for moving them about the diamond formed by the slot 24 I employ the construction which I will now proceed to describe in connection more 35 particularly with Figs. 2 to 5.

On viewing Fig. 1 it will be observed that at the four corners of the diamond represented by the bases 25, 26, 27 and the home plate 28 I have illustrated a plurality of 40 sprockets 45, 46, 47, 48, mounted on shafts having vertical axes as indicated at 49 and supported in position by the bottoms 22 and 23. A continuous chain 50 passes around said sprockets and is disposed substantially 45 immediately below the slot 24 for a purpose shortly to be defined. On the shaft 51 of the sprocket 48 is mounted a pinion 52 connected by a chain 53 to a sprocket 54 on a vertical shaft 55 which is extended through 50 the bottom 23 and provided with a hand wheel 56 whereby it may be rotated and thereby motion imparted to the chains 53 and 50.

Referring now more particularly to Figs. 55 to 5, it will be observed that for the purpose of conveying the base runners 40 about the diamond I provide at equal intervals on the chain 50 vertical extensions 60 each having a horizontal portion 61 supporting a 60 conveyer device which comprises a base 62, a spindle 63 passing through said slot 24 and a head 64 having sides 65, 65, which are turned over as indicated at 66, 66, whereby the base 67 of the batsman 40, may be 65 wedged thereinto, such base 67 preferably

having a reversely turned portion 68 engaging with a spring clip 69 carried on said head 64 whereby the figure 40 may at will be frictionally and yieldingly resistantly engaged by said head 64, or manually released 70 therefrom with the greatest facility.

Referring now more particularly to Figs. 6 to 10 wherein I have illustrated the figure representing the batsman 36 carrying a bat 37, which figure is in all respects the same 75 as that of the pitcher 38 carrying the bell 39 (Fig. 1) save in the substitution of a bat 37 for such bell 39, it will be observed that the figure 36 here shown is integral and preferably has cast engagement with the 80 pivoted staff 70, which I find desirable since these figures are preferably made of a low grade of britannia metal and the employment of such material does not give the desired rigidity for the mountings of the operating mechanism in view of the relative softness of such metal, whereas in my improved construction of such operating mechanism all mountings and moving parts may be readily made of metal of desired degree of 85 hardness and rigidity.

In viewing Fig. 6 it will be observed that the pivoted staff 70 passes through an opening in the false bottom 23 and through openings in the oppositely disposed ends 71, 72 of 90 a yoke 73 which may be connected by screws 74 to a plate 75 mounted on said bottom 23. The yoke 73 has fixed thereto by means of a screw 74^a a ring 75^a having a plurality of notches 76 for engagement with one end of 100 the helically coiled driving spring 77, the opposite end whereof bears against an arm 78 carried by said staff 70 and is secured against rotation thereon by means of a set screw 79. For holding the figure 36 in partially rotated position ready to throw or bat the ball, I employ a lever 80 pivotally mounted in an opening in the plate 75, such lever being provided with a detent 81 normally pressed downward for engagement with the 110 arm 78 by means of a helically coiled spring 82 encircling a shaft 83 which passes through a portion of said lever 80 near said detent 81 and is conveniently riveted over a washer 84 as indicated at 85, the opposite end of 115 said lever 80 being provided with a trigger arm 86 whereby said detent may be released and the figure 36 rapidly restored to its usual position by the action of the spring 77.

In playing the game of baseball by the 120 operation of the present apparatus, all of the figures representing the players 40 are withdrawn from the conveyer heads 74 and laid at a convenient position adjacent the corners of the diamond as shown in Fig. 1. The ball is placed in the cup 39 of figure 38 and the figures 38 and 36 are then given a partial turn clockwise from their position shown in Fig. 1. This in each case will tend to wind the coils of the helically coiled 125 130

spring 77, placing such spring under tension. The figures being now set for operation, the triggers 86 of the respective figures may be released simultaneously or successively, at 5 the discretion of the players of the game. Since the edge of the yoke 73 acts as a stop for the lever arm 78, in the case of the pitcher the sudden stop will cause a catapulting of the ball from the cup 39, and in the case of 10 the batter, if the operator of the trigger controlling the movement of the batter is properly timed, the bat 37 will strike such ball in its flight. Otherwise the ball will in a number of cases fall into the bag or basket 35^a of 15 the catcher 39^a. If the ball is struck by the bat 37 it will in certain cases fall into one of the bags 35. If the ball is not caught at the proper time by one of the bags 35 or 35^a, the player controlling the batsman may insert 20 one of the figures 40 into the conveyer head 74 adjacent the home plate and by rotating the hand wheel 56 move such figure along the diamond indicated by the slot 24 toward the several bases successively, all according 25 to the rules of the game.

Having thus described my invention and illustrated its use, what I claim as new and desire to secure by Letters Patent is:

1. A device of the character described comprising, in combination, a slotted casing, a figure disposed exteriorly of said slot, conveyer means within the casing for moving said figure relatively to said slot and a support above the casing, a member attached to 30 said support projecting through the slot in said casing and attached to said conveyer and means for detachably connecting said figure to said support.

2. A device of the character described comprising, in combination, a slotted casing, a figure disposed exteriorly of said slot, conveyer means within the casing for moving said figure relatively to said slot, and yieldingly resistant engaging means arranged 40 transversely with respect to said conveyer means for detachably connecting said figure and said conveyer means.

3. A device of the character described comprising, in combination, a slotted casing, a figure disposed exteriorly of said slot, conveyer means within the casing for moving said figure relatively to said slot, engaging means interposed between said conveyer means and said figure for preventing lateral 50 movement of said figure, and additional engaging means for preventing longitudinal

movement of said figure relative to said conveyer means.

4. A device of the character described comprising in combination with a base, a rotatable figure extending upwardly from said base provided with an extension adapted to act upon a free object, and a helical spring for rotating said figure substantially concentric with respect to the axis of rotation 60 of said figure, a rotatable member connected to one end of the spring and a notched ring for holding said member in a plurality of different angular positions to change the tension of said spring, whereby the speed of 65 rotation of said figure may be varied.

5. A device of the character described comprising, in combination with a base, a rotatable figure extending upwardly from said base provided with an extension adapted to 70 act upon a free object, a helical spring concentric with the axis of said figure for rotating said figure below said base, a detent projecting through and above said base for releasing said spring adapted to rotate about 75 a horizontal pivot, and spring means for holding said detent in engaging position.

6. A device of the character described comprising, in combination with a base a rotatable figure extending upwardly from said 80 base provided with an extension adapted to act upon a free object, a helical spring for rotating said figure substantially concentric with respect to the axis of rotation of said figure, a member rotating with said figure, 85 a stop for limiting the movement of said member, and a detent adapted to engage said member when in its retracted position.

7. A device of the character described comprising, in combination with a base, a rotatable figure extending upwardly from said 90 base provided with an extension adapted to act upon a free object, a helical spring for rotating said figure substantially concentric with respect to the axis of rotation of said figure, an arm rotating with said figure, a stop for limiting the movement of said arm, and a detent arranged to rotate about a 95 horizontal pivot and adapted to engage said arm when in its retracted position.

In testimony whereof I have hereunto signed my name in the presence of the two 100 subscribed witnesses.

CHARLES EDMOND DELLENBARGER.
